UNITED STATES PATENT OFFICE.

OERTEL H. LEMKE, OF MILWAUKEE, WISCONSIN.

MAGNETO.

1,125,349.

Specification of Letters Patent.

Patented Jan. 19, 1915.

Application filed July 2, 1913. Serial No. 776,950.

To all whom it may concern:

Be it known that I, OERTEL H. LEMKE, a citizen of the United States, residing at Milwaukee, in the county of Milwaukee and 5 State of Wisconsin, have invented new and useful Improvements in Magnetos, of which the following is a specification.

This invention relates to electric generators of the "magneto" type used for producing current for ignition in internal combustion engines.

It is a purpose to improve the construction and arrangement of the parts whereby the reversal of the internal combustion engine will not result in impairing the efficiency of ignition when a magneto of this type is employed.

An important object of the invention is to simplify the construction of the timing, 20 commutator and circuit breaking mechanism, whereby it will be cheap to manufacture, and will be liable in a minimum degree to derangement in use.

Additional objects and advantages will 25 appear from the following description and from the drawings, in which,

Figure 1, is an elevation of a magneto constructed in accordance with my invention, in position for forward operation of 30 an engine. Fig. 2, is a longitudinal sectional view of the magneto.

There is illustrated a shaft 10 which may be operated in conjunction with an internal combustion engine in the familiar way, 35 these details being so well understood in the art that they are not illustrated. Or, the shaft 10 may be a continuation of the crank shaft of the engine, as my invention is such as to enable this type of magneto to be 40 mounted directly on the engine shaft, saving the necessity for additional bearings, and the extra shaft and operative connections. The necessary parts may be built in the engine casing or frame, and the fly 45 wheel, or in any independent magneto to be used with a reversing engine. The particular magneto here illustrated as one of the possible embodiments of my invention is of the familiar type, in which a non-rotating armature 11 and field is used, and the field is caused to oscillate by rotating iron wings 12 carried on the shaft 10. The armature is concentric with the shaft, and the field is produced by permanent magnets 55 13 embracing the armature. The magnets

13 embracing the armature. The magnets are formed of thin stamped sheet steel blanks of any suitable number fixed together and are supported for pivotal movement on the shaft by means of suitable 60 bearing brackets 13^a mounted on the shaft 10 as shown, or otherwise. Secured to the shaft adjacent the magnets there is an interrupter cam 14 of ordinary type comprising a collar having a concentric periphery interrupted by an eccentric lug 15 at one point.

An advance, retard and reverse lever 16 is provided having a collar 17 at its lower end engaged revolvably on the shaft, the lever being tangent thereto and extending 70 up beside the bight 18 of the adjacent magnet. The lever is provided with a spring pressed pin 19 projected toward the magnets and adapted to engage alternatively in the sockets 20 and 21 formed in the plate 75 28^a on the magnet, whereby the lever may be held adjustably in either of two positions with relation to the magnets, for a purpose to be explained. Loosely pivoted on the lever there is a brush arm 22 having a nib or finger 23 at its lower end arranged to engage the cam 14 adjacent that side of the collar 17 opposite the base of the lever. A spring 22^a is coengaged between the lower part of the arm and the 85 lever to hold the nib against the cam. The outer end of the arm 22 is extended parallel with the lever for a distance on the opposite side from the nib 23 and is provided with a contact spring 24 having the 90 usual platinum point 25 thereon arranged in registry with a similar point 26 on the adjusting screw 27 on the lever. The screw 27 is engaged in a bushing 28 fixed on the lever and suitably insulated, and a wire 29 95 leads therefrom to the armature. The screw 27 is adjusted to bear upon the spring with the arm 22 at the inner limit of its movement on the lever but is sufficiently rigid and limited in action to allow it to swing 100 out from the contact 26 when the nib encounters the eccentric 15 on the cam. By means of the wire 29 a ground is made through the arm 22, and a wire 30 leads from the opposite terminal to the coil or igniter, 105 as the case may be, this circuit being well understood.

The principles of generating and using the current in all magnetos constructed in accordance with my invention, either of the 110

high or low tension type is the same as are involved in the ordinary forms of generators.

It will be understood that the cam is so timed in its movement that the break may occur at the time when a charge is to be ignited. There is a point in the movement of the wings, and in magnets with rotating armatures a similar point in the movement 5 of the armature, with relation to the magnets, where the action resultant on the break is most efficient. The socket 20 is located so as to hold the lever in position to cause the break at this moment of maximum efficiency 10 under forward rotation of the shaft 10. The magnets are moved by the lever, so that when the lever is moved for advancing the time of ignition, the magnets are also moved, on their bearings and the break always 15 occurs when the most efficient spark will be produced. Any customary means may be provided for holding the lever and magnets in their various positions for timing the spark. The socket 21 is so positioned that by shifting the lever, the relation of the wings and magnets will be such as to produce the most efficient spark should the engine and shaft 10 be reversed. It will be seen that the spark may be advanced and 20 retarded with the engine running in either direction without diminished efficiency therein.

It will be appreciated that the principle of construction of this invention may be utilized in either high or low tension devices, and may also be applied to magnetos having ordinary rotating armatures which it is believed will be sufficiently understood without specific illustration. Also the current 25 may be distributed by any customary commutator construction to a plurality of spark plugs.

In the event that the device is used on a built-in dynamo, and a multiplicity of sta-

tionary coils, with a multiplicity of magnets on a fly-wheel or the like, it will of course be understood that the principle of my invention may be used equally well, the coils being arranged for movement by a controlling lever, as they would then be corresponding to the magnets in the present embodiment of the device. 45 50

What is claimed is:

1. In a magneto, means for producing a magnetic field, an armature in the field, a mounting for the field producing means whereby it may be rotated concentrically, means for causing relative movement of the field and armature, a cam synchronously operative with said last named means, a lever pivoted concentrically with the pivotal axis of the field, an interrupter device movable by the lever operatively connected with the cam, and adjustable connections between the lever and field, producing means for adjustment of the relations of the field and interrupter, and synchronous movement of the field and interrupter in their various adjusted relations. 55 60 65

2. In a magneto of the class described a pivoted magnet movable in the arc of relative movement of armature and field, an interrupter device for interrupting the current generated, means for timing the action of the interrupter, including a lever pivoted 70 75 on a common axis with the magnet pivot and closely adjacent the magnet, a spring pressed sliding pin engaged through the lever, sockets being formed in the magnet spaced concentrically from its pivot to receive an end of the pin. 80

In testimony whereof I have hereunto set my hand in presence of two subscribing witnesses.

OERTEL H. LEMKE.
